UNITED STATES PATENT OFFICE.

FERDINAND ZOGBAUM, OF NEW YORK, N. Y., ASSIGNOR TO WESTERN ELECTRIC COMPANY, INCORPORATED, OF NEW YORK, N. Y., A CORPORATION OF NEW YORK.

SIGNALING SYSTEM.

Application filed November 18, 1921. Serial No. 516,078.

This invention relates to signaling systems, and more particularly to systems for indicating the operation of remotely controlled power switches.

5 It is an object of the invention to provide an alarm system including an audible and a visible signal.

One feature of the invention comprises a supervisory system for remotely controlled 10 devices wherein each device is connected to a relay through a single metallic conductor whereby a signal indicative of the operation of the device may be relayed to the indicating apparatus remote therefrom.

15 Another feature is the provision of a system for the supervision of remote switches comprising a bell alarm to indicate the operation or change in position of any switch in the circuit in addition to the use of individual indicating lamps which designate the 20 position of the particular switch operated.

A polarized receiving relay is provided for each power switch in the circuit, each of these relays having a contact which opens 25

for a short period while the relay armature is passing from one side to the other due to the operation of a power switch at the 30 substation. The operation of any of these polarized relays momentarily deenergizes a neutral relay which is normally energized by battery over a circuit including contacts associated with the polarized relays. The 35 momentary deenergization of this relay allows an impulse of current to flow from the battery to a second neutral relay of the slow releasing type which remains energized for a given period, closing its contact and 40 operating the bell alarm.

Other objects and features of the invention 45 will appear from a consideration of the following description taken in conjunction with the accompanying drawing and the appended claims.

The drawing shows a schematic illustration 50 of the invention in its preferred form, only so much of the substation circuit being shown as is necessary to a complete understanding of the invention.

Referring to the drawing, a plurality of 55 power switches 1, 2 and 3 are located at a sub-station, or at a plurality of sub-stations, and are controlled either by manual operation or by any suitable remote-control system, not shown in the drawing. The power 60 switch 1 carries a contact 4 which is de-

signed to engage with one or the other of contacts 5 and 6 connected to a source of current supply 45. The switch 2 carries a corresponding contact 7, adapted for engagement with either of contacts 8 or 9; while 60

the switch 3 is provided with a contact 10 and associated contacts 11 and 12. Whether the contact 5 or 6 is engaged by switch contact 4 depends upon the position of the power switch 1. Similarly, the positions of 65

the switches 2 and 3 determine the respective positions of their contacts. The power switches are merely provided with additional contacts so that upon opening or closing, a circuit will be completed through the 70

respective contacts for effecting the operation of indicating mechanism at the central control station, as will be hereinafter described. The contact 4 of power switch 1 is connected by means of line wire 13 to a 75

polarized relay 14 with which is associated a pair of electric lamps 15 and 16, at the central station. The contact 7 of switch 2 is connected through line wire 17 to a polarized relay 18, which has associated with it 80

lamps 19 and 20; while the switch contact 10 is connected through the line 21 to the relay 22 with which there are associated the lamps 23 and 24. One or the other of each 85

of these pairs of lamps is normally lighted, current being supplied thereto by a battery 25 through contacts associated with the polarized relays. The energizing current for 90

the polarized relays is provided by the source of current 45 which may be located at the substation, as shown in the drawing. Thus, 95

the attendant at the central station, by observing the lamp that is lighted is informed of the position of any given switch. In practice, it is preferred to have the lamps 15, 19 100

and 23 green, and the lamps 16, 20 and 24, red. The lighting of a red lamp informs the attendant that a certain power switch is closed, while the lighting of a green lamp will at once indicate that a particular switch 105

has been moved to the open position. A bell 26 which is common to all the polarized relays is provided to sound an alarm upon the operation of any power switch in the series. The bell 26 is controlled by the operation 110

of a neutral relay 27 of the slow releasing type. The relay 27, in turn, is controlled by the operation of a second neutral relay 28. The relay 28 is normally energized over a circuit extending from the positive 115

56 switch 1 carries a contact 4 which is de-

side of battery 25, conductors 40 and 41, through a contact such as 29 of relay 14, a contact 30 of relay 18, a contact 31 of relay 22, winding of relay 28, to the negative side 5 of battery 25.

The operation of the system is as follows: The main contacts of the power switch 1, not shown, are considered to be open, the auxiliary contact 4 being in engagement with contact 6, completing a circuit from the negative side of battery 45, switch contacts 6 and 4, line 13, through the windings of polarized relay 14 to ground. Negative potential thus applied to the polarized relay 14 causes it to close its associated contacts 29 and 32, the closing of contact 32 short circuiting the lamp 16 and lighting the lamp 15 over a circuit extending from the positive side of battery 25, lamp 15, conductor 42, contact 32 of the relay 14, conductor 43, to the negative side of the battery. When the switch 1 is closed, contact 4 is moved into engagement with contact 5 completing an energizing circuit for polarized relay 14 which may be traced from the positive side of battery 45, contacts 5 and 4 of power switch 1, line 13, through the windings of polarized relay 14 to ground. Upon operating, relay 14 closes contact 33, short-circuiting lamp 15, and also closes contact 34, providing a circuit for the lamp 16 which may be traced from the negative side of battery 25, lamp 16, conductor 42, contact 33 to the positive side of battery 25. As the contact 32 opens while the relay armature is passing from one side to the other, the neutral relay 28 is momentarily deenergized, closing its contact for an instant. The relay 28 in deenergizing releases its armature and establishes a circuit from the positive side of battery 25, conductor 40, through the winding of relay 27, armature and contact 35 of relay 28, to the negative side of battery 25. This allows an impulse of current to energize the relay 27, causing it to close its contact and complete a circuit for the bell 26 which extends from the positive side of battery 25, conductor 40, contact 36 of relay 27, through the bell 26 to negative side 40 of battery 25. Since the relay 27 is of the slow-releasing type, it holds for a period of time sufficient to ring the bell 26. However, as the armature of polarized relay 14 moves from one side to the other, after 45 breaking the contacts 29 and 32 causing an operation of the bell 26, as just described, it closes the contact 34, completing an energizing circuit for the neutral relay 28 which extends from the negative side of the battery 25, through the winding of the relay 28, through contact 31 of polarized relay 22, through contact 30 of polarized relay 18, through contact 34 of polarized relay 14 to the positive side of battery 25. The circuit 55 thus established energizes the relay 28, caus-

ing it to open contact 36, thus cutting-off battery to the relay 27, upon the deenergization of which the operating circuit of the bell 26 is broken. The operation of the system upon the change in position of any other switch, such as switches 2 or 3 is substantially the same as that described for switch 1.

What is claimed is:

1. In a system for indicating the operation of electrical apparatus, a central station, a remote station, a power switch at said remote station, a polarized relay at said central station, a circuit including said polarized relay and controlled by said power switch, a pair of indicating devices, an energizing circuit for said indicating devices, means controlled by said polarized relay for selectively rendering one of said indicating devices inoperative, a relay at said central station, a circuit for normally energizing the same, a slow releasing relay, a circuit therefor including a back contact of said normally energized relay, an alarm device, means operated by said slow releasing relay for actuating the same, and means for momentarily de-energizing said normally energized relay upon the operation of said switch controlled relay to operate said alarm device. 95

2. In a system for indicating the operation of electrical apparatus, a central station, a remote station, a plurality of power switches at said remote station each connected with said central station by a conductor individual to each switch; a plurality of polarized relays at said central station each controlled by the operation of its corresponding power switch over said conductor a pair of electric lamps associated with 105 and controlled by each polarized relay to indicate the operation of its respective switch, an energizing circuit for said lamps, means controlled by each of said polarized relays for selectively rendering one of its associated lamps inoperative, a plurality of contact members on each of said polarized relays, a relay at said central station, a circuit therefor including contacts of said polarized relays, a slow-releasing relay, a circuit therefor closed upon the deenergization of said first mentioned relay, an alarm device, a circuit therefor closed by the operation of said slow-releasing relay, whereby the operation of the contact members associated with any polarized relay momentarily breaks the circuit of said normally energized relay to momentarily energize said slow-releasing relay to operate said alarm device. 110 120 125

In witness whereof, I hereunto subscribe my name this 15th day of November, A. D., 1921.

FERDINAND ZOGBAUM.
